UNITED STATES PATENT OFFICE

WADE H. REICHARD, OF ROCHESTER, NEW YORK, ASSIGNOR TO GENERAL RAILWAY SIGNAL COMPANY, OF ROCHESTER, NEW YORK

AUTOMATIC TRAIN CONTROL SYSTEM

Application filed July 14, 1928. Serial No. 292,654.

This invention relates to automatic train control systems, and more particularly to electro-pneumatic car-carried apparatus for such systems.

5 In a train control system of the continuous inductive type, to which the present invention is more particularly applicable, it is necessary to provide against restrictions imposed due to a train passing over cross-overs, 10 switch points, frogs or from one block into another at stagger joints, commonly called "dead sections", and in accordance with the present invention this is proposed to be accomplished by delaying the imposed restriction for a time by the use of pneumatic apparatus. Also, in a train control system of the permissive type, such as the proposed system, where the train may proceed in response to the manifestation of vigilance by 15 the engineer, by operating a suitable acknowledging device, it is proposed to require such acknowledgment at repeated time intervals as determined by a pneumatic time measuring apparatus.

20 More specifically it is proposed in accordance with the present invention to sound an audible signal a predetermined period of time after a train has entered adverse territory, this interval of time being such that the audible signal is not sounded when a train passes over a "dead section", to sound this audible signal for a predetermined period of time thereafter, to impose an automatic brake application if the engineer has 25 not manifested his vigilance during the sounding of said audible signal, and to measure these intervals of time by pneumatic apparatus which depends for their proper functioning upon the venting of fluid pressure from reservoirs of predetermined capacities through restricted openings of a predetermined size. Further, it is proposed to require the act of acknowledgment to take 30 place after repeated time intervals which are measured by a similar pneumatic apparatus.

Other objects, purposes and characteristic features of the invention are in part obvious from the drawing and will in part be pointed out in the specification hereinafter.

In describing the invention in detail reference will be made to the accompanying single sheet of drawing, in which the car-carried and trackway apparatus of a train control system embodying the present invention has been conventionally illustrated.

Trackway apparatus

For the purpose of illustrating a complete system the simplified trackway apparatus of a portion of the system has been illustrated, which includes the track rails divided into blocks by insulating joints 2, of which the block I and the adjacent ends of two other blocks H and J have been shown. Since the various blocks in automatic signal territory are the same it is deemed sufficient to describe the parts of certain blocks only, and like parts of other blocks have been assigned like reference characters having distinctive exponents. At the entrance of each of these blocks is preferably provided a suitable wayside signal Z, which may be of any suitable construction, and has been illustrated as comprising a semaphore signal. These signals are controlled by track circuits in the usual manner, and the control apparatus therefore, except said track circuits has for convenience been omitted. Each of the blocks includes the usual track battery 3 and the usual track relay T. A transformer 4 is preferably connected in series with each of the track batteries 3 for the purpose of superimposing upon the direct current supplied by said track battery an alternating current derived from the transformer 5 having its primary winding connected to a suitable transmission line 6, this alternating current being only supplied in the event that the next block in advance is unoccupied as indicated by the contacts 8 of the track relay T, which contacts are only closed when the block next in advance is clear.

Car-carried apparatus

On the car is contained a suitable polyphase relay CR, which has one of its windings 10 connected to the winding of one car element 11, and has its other winding 12 connected to the winding of another car ele-

ment 13 through a suitable amplifier A. By this arrangement current is caused to flow in one winding of the relay in accordance with the flow of current in one rail of the track, and current is caused to flow in the other winding of the relay in accordance with current in the other rail of the track-way, these currents being however amplified by the amplifier A. Suitable means is also 10 preferably provided whereby the current in one of the windings of the relay is caused to be displaced in phase with respect to the current of its corresponding car element so that a displacement of phase in the currents flowing in the main or control relay CR will result when the current flow in the two track rails are in phase, this in order to produce a torque in the main or control relay CR, which is preferably a relay of the inductive 15 type and requires such phase displacement to obtain the best results.

The car-carried apparatus also includes an electro-pneumatic valve EPV, a pneumatic relay PR, a pneumatic brake valve PBV, an engineer's brake valve EBV, having a brake valve actuator BVA associated therewith, an electric acknowledging valve EAV, reset switch RS, an acknowledging valve AV, and three air switches designated AAS, BAS, 20 and SAS respectively. The functions of these various devices are more conveniently brought out in the description of the operation of the system.

Operation

Function of the main relay. The main or control relay CR assumes its normal right hand position in which it has been shown when there is current flowing in the track 40 rails ahead of the train toward the train in one rail through the axles of the train and away from the train in the other rail, thereby energizing the electro-pneumatic valve EPV through the following circuit: beginning at 45 the terminal B of a suitable source of electric energy such as a battery, wire 20, contact 21 of the main or control relay CR, wires 22, 23 and 24, normally closed contact 25 of the reset switch RS, wire 26, winding of the 50 EPV, wires 27 and 28, contact 29 of the air switch SAS, wire 30 to the common return wire C connected to the other side of said battery.

If there is no alternating current flowing 55 in the track rails, possibly because the contacts 8 of the track relay ahead are open, the track circuit is occupied by another train ahead or the like, or the current flowing 60 therein is too small to operate the relay CR, this relay will assume its de-energized condition. If desired, the relay may be caused to operate to the left hand dotted position 65 in response to the current flowing in the same direction in both track rails to obtain some

special function in the car-carried apparatus, but for convenience this feature of the system has not been specifically disclosed.

From the foregoing it is obvious that the contact 21 of relay CR will assume the right hand position and maintain the EPV energized under clear traffic conditions ahead, and that the contact 31 will complete an energizing circuit for the clear lamp G under 70 said conditions. Also, it is noted that upon reverse energization of the relay R or de-energization thereof the caution lamp Y is energized and the electric acknowledging valve EAV is energized. It is not deemed necessary to describe specific train movements in describing the operation of the system; it being sufficient to point out how the apparatus functions under different conditions of energization of the main relay CR.

Dead sections. It is noted that with the electro-pneumatic valve EPV energized, main reservoir fluid pressure may flow from the main reservoir MR (not specifically shown) through the upper valve 32 of the device EPV 75 through the pipe 33, check valve 34, pipe 35, to the capacity reservoir R¹ and the sylphon 36. The pressure in the sylphon 36 causes the valves 37 and 38 to be held in their lower position against the force of the spring 39, so that main reservoir pressure may flow 80 from the main reservoir MR through pipes 40 and 41, valve 38, pipe 42, check valve 43, pipe 44 to the capacity reservoir R² and also to the sylphon 45. With pressure existing in the sylphon 45 the valves 46 and 47 are held in their lower position against the force of the spring 48, so that main reservoir pressure may also flow from the main reservoir MR through pipes 40 and 50, 85 through the valve 47, pipes 51 and 52, to the large cylinder of the brake valve actuator BVA. This brake valve actuator and the engineer's brake valve EBV with which it is associated are more specifically described in the patent to Charles S. Bushnell, No. 1,628, 90 454, granted May 10, 1927.

When the train, conventionally illustrated by the axle TR, passes from one clear block into the next clear block the control relay CR may be de-energized for a short time by reason of the dead section associated at the junction of two blocks, by reason of stagger joints, or the like. This de-energization of the control relay CR may cause momentary de-energization of the device EPV, but by reason of the capacity of the reservoir R¹ the de-energization of the device EPV will not cause sufficient air to escape through the restricted opening 34¹ of the check valve 34 to permit actuation of the relay PR. In other words, the provision of the restricted opening 34¹ and the reservoir R¹ delays the operation of the pneumatic relay PR to the desired extent, as determined by the volume of 100 this reservoir and the area of this orifice 34¹, 105 110 115 120 125 130

- so as not to sound the whistle W. If the train is moving very slowly the whistle might possibly sound because of the reversing of relay PR, but even if this should happen the delay imposed by the reservoir R² and the restricted opening 43¹ of the check valve 43 would prevent operation of the device EPV. Also, the ball in the check valve 34 is provided to permit quick charging of the reservoir R¹.
- 5 10 Re-energization of the control relay CR always effects re-energization of the device EPV so long as the contacts 29 of the stick air switch SAS are not opened, thus making the device EPV a stick device having a slow opening stick contact 29.
- 15 *Audible signals.* Upon entrance of a train into a caution or danger block the control relay CR is de-energized for a sufficient period to cause the pneumatic relay PR to operate in response to venting pressure from the sylphon 36. This causes air pressure to flow from the reservoir R² through the restricted orifice 43¹ through the valve 37 to the whistle W. The volume of the reservoir R² and the 20 area of the orifice 43¹ are so chosen that the whistle W is sounded for, say five seconds (or any other suitable time interval), deemed sufficient time for the engineer to manifest his vigilance. All of the air vented from the 25 reservoir R² may be caused to flow to the whistle W or another atmospheric opening 59 may be provided if desired. The ball in the check valve 43 is provided to permit quick re-charging of the reservoir R² upon restoration of the pneumatic relay PR to normal.
- 30 *Acknowledgment.* The sounding of the whistle or audible signal W advises the engineer that he is to manifest his vigilance by operating the handle 60 of the acknowledging 35 valve AV to the dotted position and back to the normal solid line position. If the engineer operates the handle 60 in this manner, air pressure is first caused to flow from the main reservoir MR to the acknowledging reservoir and is then caused to flow from the acknowledging reservoir 61, through pipe 62, valve AV, pipe 63, valve 64 now in its raised position because of the deenergization of relay CR, pipe 65, to the acknowledging 40 air switch AAS, thereby causing closure of the contacts 66, and reapplication of current to the device EPV through a circuit readily traced in the drawing and including the wires 67 and 68. Upon the reapplication 45 of current to the device EPV this device EPV and the pneumatic relay PR will be restored to normal thus preventing operation of the pneumatic brake valve PBV and an automatic brake application. In order to require 50 successive manifestations of vigilance by the engineer, and in order to prevent the engineer misusing, as by tying down, the acknowledging device, the pipe 65 is also connected through a restricted orifice RO to atmosphere, 55 which device RO includes an adjustable valve
- 70 which is adjusted to provide the desired time interval between successive acknowledging acts and which is held in its adjusted position by a seal 71. In other words, the size of the orifice through the device RO 70 and the volume of the acknowledging reservoir 61 are so arranged that the air switch AAS is held closed for, say two minutes (or any other suitable interval of time), after which the engineer is required to again 75 operate the handle 60 to its dotted position and back to its normal position to prevent a brake application. The engineer need of course not operate the handle 60 until the device EPV has been de-energized and has 80 caused the pneumatic relay PR to respond and effect the sounding of the whistle W. The electrically operated valve EAV is employed to prevent the engineer taking advantage of the acknowledging device before 85 the main relay CR is de-energized, and if desired this valve EAV may be omitted.
- 90 *Reset.* If the engineer should become incapacitated or should for some other reason not manifest his vigilance at all or should delay operation of the handle 60, the pneumatic brake valve PBV will be operated and cause venting of fluid pressure from the large cylinder of the brake valve BV, thereby causing the engineer's brake valve to be moved to the service position and effect a service brake application. Further, the venting of fluid pressure from the pipe 51 in response to operation of the pneumatic brake valve PBV will not only cause operation of the engineer's 95 brake valve but will also cause the opening of the contact 29 of the stick air switch SAS. As soon as this air switch has been operated to open its contact 29, the device EPV cannot be restored by closure of the contacts 100 66 in response to acknowledgment by the engineer, nor by restoration of the control relay CR to normal in response to a change to favorable traffic conditions ahead, and the train will be brought to a stop by the automatic brake application as just explained. With the train brought to a stop the engineer or fireman may alight to the ground and depress the push button 75 of the reset switch 105 RS, which push button 75 is so located that it is only accessible from the ground. Upon depression of the push button 75 closing the contact 81, and providing the control relay CR is energized to normal or with the relay 110 CR deenergized or reversely energized and with either the brakes applied and the contacts 76 closed or the acknowledging reservoir charged with the handle 60 in the normal position, the device EPV is re-energized 115 through one of the following circuits: (1) wire 20, contact 21, wires 22 and 23 (2) wire 67, contact 66, wires 68 and 23, (3) wire 77, contact 76, wire 78; and then through the wire 24, normally closed contacts 25 of the reset switch RS, wire 26 winding of the device 120 125 130

EPV, wires 27 and 80, normally open contacts 81 of the reset switch RS, wire 82 to the common return wire C connected to the other side of the battery containing said terminal B. This re-energization of the device EPV eventually closes contact 29 of the air switch SAS after which the push button 75 may be released. In this connection it is desired to point out that the contacts 25 of the reset switch RS will not open until after an interval of time as determined by suitable retarding means, such as the dash pot 79, after the push button 75 has been depressed, this in order to permit the circuit just traced to be closed for a sufficient interval of time to effect re-closure of the stick contact 29 of the air switch SAS. The brake air switch BAS has its contacts 76 closed when the engine-and-tender brakes are fully applied and is provided so that no acknowledgment is required when the train is standing on a siding or is in a round house with its engine brakes manually applied. This brake air switch comprises a cylinder connected to the brake cylinder and having a piston spring pressed to the position shown to hold the contacts 76 open, which piston is operated to a position to close contacts 76 when an adequate brake application has been made. This feature also relieves the engineer of the duty of making an acknowledging act when entering a caution block with the brakes manually applied, at least until the train has been brought to a stop, after which if the brakes are released acknowledgment is necessary to prevent deenergization of the device EPV.

Applicant has therefore provided comparatively simple car-carried apparatus in which a pneumatic time element device is employed to prevent the requirement of acknowledgment and prevent the sounding of the acknowledging warning signal W when a train is passing over a dead section, has provided a pneumatic time element device for allowing the engineer a predetermined interval of time during which he may manifest his vigilance by acknowledgment after the warning whistle W has started to sound, and has further provided a pneumatic time element device which fixes the frequency at which the acknowledging act should be repeated, in combination with the necessary influence communicating and control apparatus for controlling the pneumatic car-carried apparatus. Although the system has been shown rather conventionally and many of the elements thereof have been shown rather specifically it is desired to be understood that the particular illustration of the invention has been selected to facilitate disclosure of the underlying principles thereof, and that the particular showing has not been selected for the purpose of illustrating the scope of the invention, and it is further desired to be understood that various changes, modifica-

tions or additions may be made to adapt the invention, to the particular system to which it is to be applied, all without departing from the scope of the invention except as demanded by the scope of the following claims.

What I claim as new is:

1. An automatic train control system comprising, a vehicle carried control relay controlled in accordance with traffic conditions ahead of said vehicle, an electro-pneumatic valve, brake control means controlled by said electro-pneumatic valve, contacts closed only when said brake control means is in its inactive condition, a circuit for said electro-pneumatic valve including said contacts, contacts closed only when said control relay is energized, means for shunting said latter contacts if the engineer has manifested his vigilance, and other means for shunting said latter contacts if the brakes have been manually applied.

2. An automatic train control system comprising, an electro-pneumatic brake control means on a railway vehicle, including pneumatically operated contacts controlled pneumatically by said electro-pneumatic means, a relay controlled in accordance with traffic conditions ahead of said vehicle for controlling said electro-pneumatic brake control means through a circuit including said pneumatically operated contacts, and a supplemental circuit for energizing said electro-pneumatic brake control means including said pneumatically operated contacts and other contacts closed only if the engineer manifests his vigilance at repeated time intervals.

3. An automatic train control system comprising, an electro-pneumatic brake control means on a railway vehicle, pneumatically operated contacts controlled pneumatically by said brake control means, a relay controlled in accordance with traffic conditions ahead of said vehicle for controlling said electro-pneumatic brake control means through a circuit including said pneumatically operated contacts, a supplemental circuit for energizing said electro-pneumatic brake control means including said pneumatically operated contacts and other contacts closed only if the engineer manifests his vigilance at repeated time intervals, and adjustable means for determining the length of said time intervals.

4. An automatic train control system comprising, an electro-pneumatic valve on a railway vehicle including pneumatically operated contacts, a relay controlled in accordance with traffic conditions ahead of said vehicle for controlling said electro-pneumatic valve through a circuit including said pneumatically operated contacts, and a supplemental circuit for energizing said electro-pneumatic valve including said pneumatically operated contacts and other contacts

closed only if the engineer manifests his vigilance at repeated time intervals, adjustable means for determining the length of said time intervals, and means for allowing authorized persons only to change the adjustment of said adjustable means.

5. An automatic train control system comprising, a vehicle carried control relay normally energized in response to current in the 10 track rails flowing in accordance with traffic conditions ahead of said vehicle, an electro-pneumatic valve, brake control means controlled by said electro-pneumatic valve, contacts closed only when said brake control 15 means is in its inactive condition, a circuit for said electro-pneumatic valve including said contacts, contacts closed only when said control relay is energized, means for shunting said latter contacts if the engineer has 20 manifested his vigilance, and other means for shunting said latter contacts if the brakes have been manually applied.

6. An automatic train control system comprising, an electro-pneumatic brake control 25 means on a railway vehicle, pneumatically operated contacts controlled pneumatically by said brake control means, a relay normally energized in response to current in the track rails ahead of said vehicle for controlling 30 said electro-pneumatic brake control means through a circuit including said pneumatically operated contacts, and a supplemental circuit for energizing said electro-pneumatic 35 brake control means including said pneumatically operated contacts and other contacts closed only if the engineer manifests his vigilance at repeated time intervals.

7. An automatic train control system comprising, an electro-pneumatic brake control 40 means on a railway vehicle, pneumatically operated contacts controlled pneumatically by said brake control means, a relay normally energized in response to current flowing in the track rails ahead of said vehicle for controlling 45 said electro-pneumatic brake control means through a circuit including said pneumatically operated contacts, a supplemental circuit for energizing said electro-pneumatic valve including said pneumatically operated 50 contacts and other contacts closed only if the engineer manifests his vigilance at repeated time intervals, and adjustable means for determining the length of said time intervals.

8. An automatic train control system comprising, an electro-pneumatic brake control 55 means on a railway vehicle including pneumatically operated contacts, a relay controlled in accordance with traffic conditions ahead of said vehicle and depending for its 60 energization upon current flowing in the track rails for controlling said electro-pneumatic valve through a circuit including said pneumatically operated contacts, and a supplemental circuit for energizing said electro-pneumatic valve including said pneu-

65 matically operated contacts and other contacts closed only if the engineer manifests his vigilance at repeated time intervals, adjustable means for determining the length of said time intervals, and means for allowing authorized persons only to change the 70 adjustment of said adjustable means.

9. An acknowledging device comprising, cancelling means responsive to a predetermined pressure, a source of fluid pressure, a 75 reservoir, manually operable means for at times connecting said source of fluid pressure to said reservoir and at other times connecting said reservoir to said cancelling means, adjustable means for venting fluid pressure 80 from said cancelling means, and means for locking said adjustable means, whereby the frequency of operation of said manually operable means required to maintain said cancelling means active may only be adjusted 85 by an authorized person.

10. An automatic train control system comprising, an electro-pneumatic brake control means on a railway vehicle, pneumatically operated contacts controlled pneumatically 90 by said brake control means, a relay normally energized in response to current in the track rails ahead of said vehicle for controlling said electro-pneumatic brake control means through a circuit including said pneumatically operated contacts, a supplemental circuit for energizing said electro-pneumatic 95 brake control means including said pneumatically operated contacts and other contacts closed only if the engineer manifests 100 his vigilance at the repeated time intervals, and another supplemental circuit for energizing said electro-pneumatic brake control means including contacts closed only if the 105 brakes have been manually applied.

11. An acknowledging device comprising, cancelling means responsive to predetermined pressure, a source of fluid pressure, a reservoir, manually operable means for at times connecting said source of fluid pressure 110 to said reservoir and at other times connecting said reservoir to said cancelling means, adjustable means for venting fluid pressure from said cancelling means, and means for locking said adjustable means by a breakable 115 seal, whereby the frequency of operation of said manually operable means required to maintain said cancelling means active may only be adjusted without penalty by an 120 authorized person.

12. An automatic train control system comprising, a car-carried relay controlled in accordance with traffic conditions ahead of the car, an electro-pneumatic valve, pneumatic apparatus pneumatically controlled by 125 said electro-pneumatic valve having contacts associated therewith which are opened a predetermined time after said electro-pneumatic valve is deenergized, a circuit for energizing said electro-pneumatic valve including con-

tacts of said relay and the contacts of said pneumatic apparatus in series, and an auxiliary circuit for said electro-pneumatic valve including the contacts of said pneumatic apparatus and contacts closed only when the brakes are fully applied in series.

In testimony whereof I affix my signature.
